EXTENSIBLE HINGE

Filed Jan. 27, 1928

UNITED STATES PATENT OFFICE

WALTER JAMES HILL, OF BIRMINGHAM, ENGLAND

EXTENSIBLE HINGE

Application filed January 27, 1928, Serial No. 249,853, and in Great Britain February 2, 1927.

This invention is for improvements in or relating to extensible hinges for trunks, suit cases, sample cases, attaché cases, and like receptacles of variable capacity governed by 5 relative sliding or other adjustment of a complementary pair of box-like component parts of the receptacle adapted to telescope one within the other.

The type of hinge to which the invention 10 refers is that which comprises a two-part telescopic member carried by the one part of the receptacle, and a hinged member, carried by the sliding inner part of this telescopic member and adapted for attachment to or engagement with the other part of the receptacle, the parts of said telescopic member being adapted, when the receptacle is closed, to be secured together in any adjusted position by means controlled by the angular 15 opening and closing movements of the hinged member.

In order that this invention may be clearly understood and readily carried into practice, reference may be had to the appended drawings, upon which:

Figure 1 is a perspective view of an extensible hinge constructed according to the present invention.

Figure 2 is a vertical sectional elevation 30 through the hinge taken in Figure 1.

Figure 3 is a vertical sectional elevation illustrating the hinge shown in Figure 2, in the secured condition.

Figure 4 is a perspective view of the link 35 or bar shown in the three preceding figures.

Figure 5 is a perspective view of the sliding inner part shown in the Figures 1, 2 and 3.

Figure 6 is a transverse section taken on 40 line 6-6 of Figure 3.

Figure 7 is a fragmentary sectional view illustrating the independently operable securing piece hereinafter referred to.

As shown in the drawing, the hinge consists of a telescopic member comprising an outer part *g* adapted to be attached to the suit case as for instance by suitably perforated ears *g'*, and a sliding inner part *h* (see particularly Figure 14) which carries at its lower part a hinged member *i*. The outer part

g is of elongated box formation as illustrated, and is longitudinally slotted at *g*², whilst the sliding inner member *h* is of inverted channel section and is provided with a spring detent or pawl *h'* having a lateral tooth *h*², (see 55 particularly Figure 5) adapted to co-operate with ratchet teeth *g*³, provided on the back of the outer part *g*. *j* is the link of channel section, and provided at one extremity with a pin *j'* adapted to slidably co-operate with a staple *i'* carried by the hinged member *i*, and at the opposite extremity with a pin *j*² adapted to slide in the slots *g*² and take a bearing in or engage the sliding inner part *h* as at *h*³ (Figure 14). *j*³ is a hook shaped 60 claw or projection provided upon the link *j*, and adapted to lie beneath a laterally extended part *h*⁴ (see particularly Figure 14) of the detent or pawl *h'*, said claw *j*³ operating in an elongated slot *g*⁴ in the outer 65 part *g* and slot *h*⁵ (see particularly Figures 2 and 5) in the sliding inner part *h*. *j*⁴ (see particularly Figures 2 and 4) is a blade spring attached to the underside of the link *j*, tending normally to tilt same to the 70 position shown in Figure 2, thereby rocking the hinged member *i* and so dispensing with the usual coil spring associated with its pivot *i*².

In operation it will be seen that the hinged member *i* normally assumes the condition shown in Figures 1 and 2, on account of the spring *j*⁴ bearing upon the outer part *g*. In this condition it will be seen that the claw or projection *j*³ has raised the detent or pawl *h'* away from the ratchet teeth *g*³, thereby rendering same ineffective and enabling the telescopic parts to be slid into any desired position of adjustment at will. When the desired position of adjustment has been obtained, the hinged member *i* is moved into alignment with the telescopic parts *g* and *h*, the claw or projection *j*³ assuming the position shown in the Figure 3, and permitting the detent or pawl *h'* to engage the ratchet teeth *g*³, thus positively preventing any extension of the hinge.

The telescopic parts *g* and *h* can, however, in this condition be closed or collapsed, this being desirable where a case of variable ca- 100

pacity after being fastened is so filled that it may be reduced by a simple pressure applied to the upper part of the case.

It has been found, however, that this collapsing of the case after it has been filled is sometimes deficient inasmuch as a comfortably filled case may have very heavy luggage placed thereon and on further collapse of the case consequent damage to the articles obtained therein. To avoid this, an independently operable member may be associated with the telescopic mechanism in the manner illustrated in Figure 7. *k* is the member pivotally mounted upon extensions of the pin *j*² and provided with a peg or pin *k'* adapted to be engaged with any one of a plurality of apertures *g*⁵ in the outer part *g* by manipulation. That is to say, when the mechanism has been brought to the position shown in Figure 3, the member *k* may be pressed by the finger so that its pin *k'* engages any one of the apertures *g*⁵, and thereby positively fastens the telescopic elements so that no collapse or extension thereof can positively take place. When the hinged member *j* is released and rocked on its pivot, by the spring *j*⁴, the link *j* disengages the member *k* and renders same inoperative. The member *k* may be normally held in the position illustrated relative to the link *d* as for instance by friction.

It will be appreciated that instead of employing ratchet mechanism in the present invention, such as that illustrated, a tooth *h*² on the detent or pawl *h* may be adapted to come between plain teeth on a rack instead of ratchet teeth *g*³, so that the two telescopic elements are positively secured in position. When the mechanism assumes the position shown in Figure 3, neither collapse nor extension can take place.

What I claim as my invention and desire to secure by Letters Patent is:—

1. An extensible hinge for a receptacle of variable capacity, comprising in combination a two-part telescopic member, a hinged member pivoted to the sliding inner part thereof, and a link device connecting the said sliding inner part with the hinged member externally of the telescopic member, and adapted to be displaced into adjacency with the said telescopic member to secure the parts thereof against extension.

2. An extensible hinge for a receptacle of variable capacity, comprising in combination a two-part telescopic member, a hinged member pivoted to the sliding inner part thereof, a link device pivotally connected to said sliding inner member at its one extremity and to the hinged member at its opposite extremity externally of the telescopic member, and adapted to be displaced into adjacency with the telescopic member to secure the parts thereof against extension.

3. An extensible hinge for a receptacle

of variable capacity, comprising in combination a two-part telescopic member, a hinged member pivoted to the sliding inner part thereof, a link device pivotally connected to said sliding inner member at its one extremity and slidably pivoted to said hinged member at its opposite extremity externally of the telescopic member, and adapted to be displaced into adjacency with the telescopic member to secure the parts thereof against extension.

4. An extensible hinge, comprising in combination a two-part telescopic member, a hinged member pivoted to the sliding inner part thereof, a link pivoted to said hinged member and adapted to slide relative to said sliding inner part, said link being provided externally of the said telescopic member and adapted to be tilted to secure the two parts of said telescopic member against extension.

5. An extensible hinge for a receptacle of variable capacity, comprising in combination a two-part telescopic member, a hinged member pivoted to the sliding inner part thereof, an internal catch mechanism disposed within the telescopic member adapted to secure the sliding inner part in relation to the stationary outer part, and means controlling said catch mechanism comprising a link externally connecting the sliding inner part with said hinged member.

6. An extensible hinge for a receptacle of variable capacity, comprising in combination a two-part telescopic member, a hinged member pivoted to the sliding inner part thereof, a link pivoted to the sliding inner part at its one extremity and having a sliding pivotal connection with said hinged member at its other extremity, a claw upon said link adjacent its pivot with the sliding inner part, and a catch device operable by said claw adapted to secure the two parts of the telescopic member against extension.

7. An extensible hinge for a receptacle of variable capacity, comprising in combination a two-part telescopic member, a hinged member pivoted to the sliding inner part thereof, a link pivoted to the sliding inner part at its one extremity and having a sliding pivotal connection with said hinged member at its other extremity, a claw upon said link adjacent its pivot with the sliding inner part, and a catch device attached to the sliding inner member adapted to co-operate with ratchet teeth on the outer member and be lifted therefrom by the claw.

8. An extensible hinge for a receptacle of variable capacity, comprising in combination a two-part telescopic member, a hinged member pivoted to the sliding inner part thereof, a link pivoted to the said sliding inner part at its one extremity and to said hinged member at its opposite extremity, and adapted to be displaced into adjacency with the telescopic member to secure the parts thereof against extension.

thereof against extension, and a spring carried by said link adapted to bear upon the outer part of the telescopic member tending to normally tilt the link.

- 5 9. An extensible hinge comprising in combination a two-part telescopic member, a hinged member pivoted to the sliding inner part thereof, a link connecting the said sliding inner part with said hinged member,
10 and adapted to be displaced into adjacency with the telescopic member to secure the parts thereof against extension, and an independently operable piece associated with the telescopic member adapted to positively
15 secure same together and be automatically released upon the tilting of said link.

In witness whereof I have hereunto set my hand.

WALTER JAMES HILL.
